UNITED STATES PATENT OFFICE.

HENRY GRASMERE, OF NEWARK, NEW JERSEY.

DESIGN FOR A SWIVEL CATCH.

Application filed February 25, 1928. Serial No. 25,585. Term of patent 3½ years.

To all whom it may concern:

Be it known that I, HENRY GRASMERE, a citizen of the United States, residing at the city of Newark, in the county of Essex and State of New Jersey, have invented a new, original, and ornamental Design for a Swivel Catch, of which the following is a specification, reference being had to the accompanying drawing, forming part thereof.

The figure is a perspective view of a swivel catch, showing my new design.

I claim:—

The ornamental design for a swivel catch, as shown.

HENRY GRASMERE.
